RADIO CONTROL PANEL

Melvin H. Boldt, Glenview, Ill., assignor to Zenith Radio Corporation, a corporation of Delaware

Application August 28, 1958, Serial No. 52,435

Term of patent 14 years

(Cl. D26—14)

FIG. 1

FIG. 3

FIG. 2

Figure 1 is a front elevational view of a radio control panel showing my new design;

Figure 2 is a perspective view of my design; and

Figure 3 is an enlarged fragmentary view, partially in section, taken along line 3—3 of Figure 1.

The indicia, shown by means of dashed lines in Figure 1, are illustrative only.

I claim:

The ornamental design for a radio control panel, substantially as shown and described.
